JOHN A. HAHN AND CHARLES VOGLER, OF DEGRAFF, OHIO.

Letters Patent No. 77,607, dated May 5, 1868.

IMPROVEMENT IN SHOEMAKER'S BENCH.

The Schedule referred to in these Letters Patent and making part of the same.

TO ALL WHOM IT MAY CONCERN:

Be it known that we, JOHN A. HAHN and CHARLES VOGLER, of Degraff, in the county of Logan, and State of Ohio, have invented a new and improved Shoemaker's Bench; and we do hereby declare that the following is a full, clear, and exact description of the same, reference being had to the annexed drawings, making a part of this specification, in which—

Figure 1 is a side elevation.

Figure 2 is an end elevation.

Figure 3 is a top view.

Figure 4 is a cross-section, showing the spindle J.

The object of this invention is to provide a neat and convenient bench for the use of shoemakers, which shall have on one side of the operator an adjustable clamp of improved construction, and on the other side an adjustable rotating jack, for holding boots and shoes during the operation of pegging.

In the drawings, A represents the seat or platform of the bench, supported upon suitable legs B B. On one end of the bench is a clamp, C, composed of one jaw, c, which is movable only vertically, and another, c', which is movable both vertically and laterally. The jaw c' is hinged at its lower end to the jaw c, and can be clamped against it with great power by means of a cam-lever, D, operated by an arm, E, and treadle F. By pressing down on the treadle F, the operator obtains the power of two levers, F and D, and of the cam on the latter lever, by which to operate the clamp. A spring, s, is employed to force the two jaws of the clamp asunder. The jaw c extends a short distance below the other jaw, and is bolted or otherwise suitably attached to a cross-bar, G, supported in mortises or slots in two of the legs, and capable of being adjusted up and down by means of pins and holes e e e. By this means the clamp C can be adjusted higher or lower, to suit the convenience of the workman.

The jaw c may be held firmly in position, while the other jaw is operating against it, by means of an arm or projecting end of a beam, H, behind it. If bolted to that beam, the bolt may work in a slot in the jaw, so that the latter can move up and down without difficulty.

On the opposite end of the bench is a plate, I, which is supported by, and rotates horizontally upon, a spindle, J, which stands vertically in an opening through the bench, being held in position by two metallic plates, K and L, one riveted to the upper and the other to the under side of the bench, and extending slightly over the opening just referred to. The plate I supports two blocks, one, M, fixed immovably to it, and another, N, working back and forth to and from the block M by means of a screw-rod, O.

The upper surfaces of the blocks are made concave, and fitted to receive and hold a boot or shoe in the position shown by the red lines in the drawings. A strap, r, passes around the shank of the shoe, when the latter is on the blocks, and, extending down to a treadle, T, enables the operator, by placing his foot on the treadle, to confine the boot or shoe as firmly in position as he desires, while he is at work upon it. Both the treadles T and F may have a set of notches, or a ratchet, v v, on the side of the slot in the bench-leg, through which they extend, so that they can be fastened down while the operator is at work. The plate I, with the boot or shoe upon it, can be turned to any horizontal position to suit the convenience of the workman, and the blocks M N can be adjusted to any size of shoe or boot.

The workman can sit upon the bench while at work, or upon a stool independent of the bench; or, by raising the bench upon blocks, can, without any difficulty, do all his work while standing, thereby relieving himself of the necessity of maintaining one cramped position while at work, and greatly promoting his convenience, comfort, and health.

Having thus described our invention, what we claim as new, and desire to secure by Letters Patent, is—

1. The clamp C, when constructed with the vertically-adjustable jaw c, the vertically and laterally-movable jaw c', the spring s, and the combination of the cam-lever D, rod E, and treadle F, for the purpose of operating it, the whole being constructed, arranged, and operating in the manner described.

2. The combination and arrangement, on a shoemaker's bench, of the clamp C, constructed and operating

as above described, and the apparatus consisting of the plate I, blocks M and N, screw O, strap r, and treadle T, all constructed and operating in the manner and for the purposes set forth.

To the above specification of our invention we have signed our hands, this 10th day of March, 1868.
